UNITED STATES PATENT OFFICE.

FRANK E. MARCY, OF SALT LAKE CITY, UTAH.

SCREEN-GRADE FOR BALL-MILLS.

1,153,238.

Specification of Letters Patent. Patented Sept. 14, 1915.

Application filed June 3, 1914, Serial No. 842,722. Renewed April 19, 1915. Serial No. 22,488.

To all whom it may concern:

Be it known that I, FRANK E. MARCY, a citizen of the United States, residing at Salt Lake City, in the county of Salt Lake and 5 State of Utah, have invented certain new and useful Improvements in Screen-Grates for Ball-Mills, of which the following is a full, clear, and exact description, reference being had to the accompanying drawings, 10 forming a part hereof.

My invention has relation to improvements in screen-grates for ball mills; and it consists in the novel features of construction more fully set forth in the specification 15 and pointed out in the claims.

In the drawings, Figure 1 is an end elevation of a mill employing my grate, viewed from the feed end, parts being broken away; Fig. 2 is a side elevation with parts in section; Fig. 3 is an inner face view of one-half of the grate, only one of the grate sectors and sections thereof being detailed; Fig. 4 is a transverse section through one of the sectors on the line 4—4 of Fig. 3; 25 Fig. 5 is a rear edge view of one of the grate sections; Fig. 6 is a face view looking at the slotted or recessed side of the section; Fig. 7 is an enlarged cross-section on the line 7—7 of Fig. 5; Fig. 8 is an enlarged 30 view on the order of Fig. 5, showing however a portion only, of the grate section; Figs. 9 and 10, and 11 and 12 are respectively elevations and end views of the bolts for securing the grate sectors to the drum 35 head; Fig. 13 is a view on the order of Fig. 3 showing a modified form of grate-sector; Fig. 14 is an edge view of one of the modified sectors; Fig. 15 is a rear edge view of one of the sections entering into the construction of the sector; Fig. 16 is a bottom plan of Fig. 15; Fig. 17 is a cross-section on the line 17—17 of Fig. 16; and Fig. 18 is a sectional detail on the line 18—18 of Fig. 13.

45 The present improvement is directed to the construction of grates forming the diaphragm or transverse screens of ball-mills on the order of that described in my pending application for patent for ball mills, 50 Serial Number 788,132, filed September 4, 1913, whether or not the mill be provided with radial screens such as shown in the structure of said pending application.

55 The object of the invention is to provide a grate composed of a series of radial seg-

ments or sectors, each segment being in turn subdivided into a series of transverse sections, be the latter arcuate or straight, the said sections being so formed as to leave spaces or screening interstices between them 60 for the passage of the material crushed in the crushing compartment of the mill.

A further object is to provide a grate of the character described with passages or spaces flaring slightly in the general direction of discharge of the crushed or comminuted material, the flare being however insufficient to have any material effect on the size or uniformity of the particles discharged with any wear of the plates constituting the segments or component parts 70 of the grate.

A further object is to construct a grate in which the openings are uniform; one which may be built up to any cross-sectional diameter of drum; and one possessing further and other advantages better apparent from a detailed description of the invention, which is as follows:

Referring to the drawings, and for the present to Figs. 1 to 12 inclusive, 1, represents a cylindrical (preferably cast iron) container, drum, or tumbling barrel (or equivalent tubular member) provided with a lining of silex, hard gray iron, steel or 80 equivalent layer 2, said lining being confined to the walls of the barrel and to the head 3 at the intake end of the barrel, the opposite head 4 not necessarily requiring a lining. The intake for the feed or pulp 90 is through the hollow trunnion 5, said feed entering the crushing compartment C of the mill, the crushed material or finished product discharging through the discharge trunnion 6. Forming one of the terminal 95 walls of the crushing compartment, to wit, the wall adjacent the discharge trunnion 6, and spaced from the head 4 by a series of radial vanes, blades or lifters 7 is an annular or disk-like screen or grate (or equivalent 100 diaphragm) comprising a series of radial primary segments or sectors 8 (of manganese steel), each sector being in turn made up of a series of transverse sections separable along planes or surfaces disposed substantially at right angles to the middle radius of the sector as shown. This grate is interposed beyond the end of the portion of the lining 2 disposed along the peripheral walls of the drum, the outer face of the 105 110

grate bearing against the inner edges of the lifters 7 against which it is firmly drawn by the bolts 9, 9' whose inner ends are secured to the grate, and whose outer ends are 5 passed through the head 4, suitable nuts *n* serving to tighten the parts as clearly obvious from the drawings.

The walls of the central opening of the 10 grate 8 are beveled and surround and engage a central imperforate (except at the center) disk 10 provided with a flaring hub 11 which directs the finished product (dropped by the lifters 7) into the trunnion 6, it being understood that the material 15 passing through the grate enters the radial compartments bounded by the grate sectors 8 and disk 10, the head 4, and the lifters 7, the grate sectors 8 and disk 10 being spaced from the head 4 a distance equal to the 20 widths of the lifters or blades 7, against the edges of which they bear.

The central opening of the flaring hub 11 registers with the corresponding opening of the disk 10 (Fig. 2) whereby a central or 25 axial passage is formed through these members establishing communication between the discharge trunnion 6 and the crushing compartment C, thus keeping the mill from choking up should the mill become overloaded, said axial passage allowing the material to discharge from the mill into the trunnion 6 in the usual way. As shown, the 30 peripheral surface of the hub 11 is substantially conical, but any equivalent outwardly 35 tapering (or inwardly flaring) member will answer the purpose of directing the finished product dropped by the lifters 7, into the trunnion 6. For example a pyramidal or equivalent hub suitably formed would 40 fall within my invention.

As stated at the outset, the invention herein is directed particularly to the construction of the screening grate, the features above alluded to being with one or two exceptions well understood in the art, and not herein claimed. In the grate illustrated in the figures at present considered, I provide 45 an outer ring section 12 for each grate segment or sector, the cross-section of the ring 50 being substantially as shown in Fig. 4, that is to say, the inner face of each ring section is provided with a bevel groove *h* which receives the corresponding outer marginal curved bevel edge *t* of the outer section *m* 55 of a grate sector, the sector comprising in addition to the outer section *m*, an inner imperforate section *m'*, and a series of intermediate transverse sections *m''*, the outer 60 faces of the several sections (that is to say, the faces turned toward the head 4 of the drum) being provided with perforated ears or lugs *e* which, when the sections are assembled register along radial lines, and collectively form a rib through which is passed 65 a securing bolt 13 which couples the several

sections together. Thus the individual sections of any sector are joined by the bolts 13 passed through the registering perforations *o* of the ears *e*, the sector as such being in turn connected to the head 4 by the bolts 70 9, 9'. The inner edges of the sections *m'* are beveled (Fig. 4), said bevel edges engaging the corresponding bevel edges of the plate or disk 10, the latter forming virtually an imperforate inner extension of 75 the grate composed of the sectors 8. The ring sections 12 (locked to the grate sectors by the tongue and groove connection *t*, *h*, referred to) serve as filler-in pieces between the grate sectors and the inner walls of the 80 drum. Formed along the inner face of each section *m''* (or the face which engages the outer face of an adjacent section), and at points between and exterior to the ears *e*, are recesses or depressions *d* the bases of 85 which are slightly inclined to the planes of the faces of the sector, whereby there result grate openings or passages between the several sections (*m''*), the said openings flaring toward the discharge face of the grate 90 (Fig. 4). The flare or taper of these openings however is so slight that with any wear of the inner face of the sector or that exposed to the material and grinding balls in the crushing compartment, no perceptible 95 change or enlargement in the cross-section of the passage is apparent, the finished product (after passing through the grate) being substantially uniform in size. The 100 grate is constructed to deliver material crushed from one-sixteenth to one-eighth inch. In other words, where the feed is crushed down to 8 or 16 mesh the present 105 grate is employed; where it is crushed finer, finishing screens are used, as in my pending application aforesaid, no claim being made herein however for a combination of grate and screens.

It may be stated in passing that one of the objects herein is to reduce the amount 110 of slime, which, as well known, is always difficult of proper concentration. The securing bolt 9 for the sector 8 passes through and between two of the sections *m''* *m''*. These particular sections are necessarily 115 provided with semicylindrical depressions *r* for the passage of the bolt therethrough, the head of the bolt being received by a socket *s* formed in the sections (Figs. 3, 5, 6). Any equivalent method of giving the bolt ample purchase is however contemplated by my invention. The number of blades or lifters 7 is equal to the number 120 of sectors 8, one blade supporting two sectors opposite the radial joint or seam between the sectors (Figs. 1, 3). The terminals of the ring sections 12 are beveled (Fig. 3) whereby the end of one section overlaps the meeting end of an adjacent section along a seam or joint *x* inclined to a radial line 125 130

through the joint, the latter cutting across the edge of the blade 7 by which any two sectors 8 are supported.

In the form of grate above described, the several sections of a grate sector separate along planes or straight surfaces transverse to the central radial line through the sector. In Figs. 13 to 18 inclusive however I show a modification in which the sections are arcuate, thereby engaging and being separable along curved or cylindrical surfaces, the openings in the grate being curved as compared with the straight openings or slots in the first form described. Thus in Figs. 13, 14, the outer sector section is represented by the letter a , the inner section by a' , and the slot-forming sections by a'' , the slots d' being curved or arcuate. Like the first form described, the arcuate sections are provided with perforated ears or lugs e' on their outer faces traversed by a securing bolt 13'. In addition however, the sections a'' are provided with studs or projections 14 at the terminals and centers of their inner edges, which enter corresponding depressions or sockets t' in the outer edge of an adjacent section and thus serve to lock the sections circularly. In mills where a special finishing screening and sizing compartment C' is provided beyond the crushing compartment C for handling very fine material or that crushed finer than one-sixteenth, as in my pending application aforesaid and in many existing mills, and where it is usual to provide buckets B for directing the material toward the axis of the mill and into the discharge trunnion 6, I may employ the bucket as an abutment to prevent circular displacement of the grate by casting on the side of the outer ring 12' a lug 15 which bears against the bucket. This arrangement dispenses with the requirement of the outer through bolt 9 as shown in the first form described. It is not however claimed herein as it falls within the purview of the ordinary skilled mechanician. Except in the particulars noted the modified grate (Figs. 13 to 18) is the same as the first form described. It is apparent that the grate is susceptible of other modifications without departing from the nature or spirit of my invention.

It will be seen from the foregoing that the danger of "blinding" the screen is entirely eliminated, it being possible to keep the openings or slots (d , d') clean at all times owing to the sectional character of each grate sector. The sectors may be enlarged or reduced radially (and hence circularly) to any cross-sectional diameter of drum or mill. The planes of separation between the sections m'' of any sector are substantially parallel to the axis of rotation of the drum, the separating planes between corresponding sections of the entire series of sectors forming the faces of a prism; where-

as the corresponding separating surfaces between the sections a'' form the surface of a cylinder. In either form however the several separating surfaces from the axis of the drum to its periphery, whether prismatic or cylindrical, are concentric with the rotation axis of the drum. While I have shown the separating surfaces between corresponding sections of the several sectors continuous around the axis of the drum, it would not fall outside the spirit of my invention if said surfaces were arranged in staggered relation. In fact, I do not wish to be restricted to the specific details here shown, as they may be altered in many particulars without affecting the nature of the invention. For example, the recesses or slots d , d' , instead of being formed on the "bottom" side of any section (m'' , a''), that is to say, the side facing the axis of rotation of the drum, may be on the upper side or on the side facing the outer walls of the drum. This reversal of the formations would obviously fall under my invention. The details might be altered in other particulars not necessary here to mention. Obviously, the screen need not be limited in its application to "ball-mills" specifically; it might be used in other connections.

Features illustrated but not alluded to are well known in the art and require no description in the present connection.

Having described my invention, what I claim is:—

1. In combination with a drum rotatable about a fixed axis and provided with terminal heads having openings respectively for the feed and discharge of the material, a series of radial blades or lifters disposed on the inner surface of one of the heads, sectional grate sectors having radial meeting edges resting on the inner edges of the blades, and means for securing the sections of the sectors together at points between the blades.

2. In combination with a drum rotatable about a fixed axis and provided with terminal heads having openings respectively for the feed and discharge of the material, a series of radial blades or lifters disposed on the inner surface of one of the heads, radial grate sectors composed each of a series of sections disposed transversely to the radii of the sector, and having meeting edges resting on the inner edges of the blades, and means traversing the sectors radially at points between the blades for securing the sections to one another.

3. In combination with a cylindrical drum rotatable about its axis, a series of circularly disposed ring sections distributed along the inner walls of the drum, a series of grate sectors forming an annular grate and disposed transverse to the rotation axis of the drum, each sector comprising a series of sec-

- tions separable along surfaces transverse to the radii of the sector and provided with slot formations adjacent said surfaces of separation, an outer terminal section for each sector dovetailing with a corresponding ring section, an inner imperforate section forming the opposite end of each sector, a central disk engaging the inner sections of the respective sectors, and means for securing the parts fixedly in the drum.
4. In combination with a drum rotatable about a fixed axis and provided with terminal heads having openings respectively for the feed and discharge of the material, a series of radial blades or lifters disposed on the inner surface of the discharge head, grate sectors having radial meeting edges resting on the inner edges of the blades, and ring sections engaging the outer portions of the sectors, the ring sections forming a lap joint across the edge of the blade supporting the sectors, and means for securing the sectors to the head and into firm engagement with the blades aforesaid.
5. In a grate, a sector composed of independent sections, the sections having projections and corresponding depressions en-

gaged by said projections to prevent displacement between the sections.

6. In combination with a drum rotatable about a fixed axis and provided with terminal heads having openings respectively for the feed and discharge of the material, a series of radial blades or lifters disposed on the inner surface of one of the heads, and grate sectors having radial meeting edges resting on the inner edges of the blades.

7. In combination with a drum rotatable about a fixed axis and provided with terminal heads having openings respectively for the feed and discharge of the material, a series of radial blades or lifters disposed on the inner surface of the discharge head, grate sectors having radial meeting edges resting on the inner edges of the blades, and means for securing the sectors to the head and into firm engagement with the blades aforesaid.

In testimony whereof I affix my signature, in presence of two witnesses.

FRANK E. MARCY.
